UNITED STATES PATENT OFFICE.

ANDREW J. UPHAM, OF SYCAMORE, ILLINOIS.

WIRE-STRETCHER.

SPECIFICATION forming part of Letters Patent No. 542,296, dated July 9, 1895.

Application filed August 7, 1894. Serial No. 519,639. (No model.)

To all whom it may concern:

Be it known that I, ANDREW J. UPHAM, a citizen of the United States, residing at Sycamore, in the county of De Kalb and State of Illinois, have invented certain new and useful Improvements in Wire-Stretchers; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

15 My invention has reference to that class of wire-stretchers in which a notched bar is attached at one end, through the medium of a chain or hook, either to a post or to one end of a wire to be spliced, as the case may be, 20 and passed through a hand-lever provided with an operating-pawl and a retaining-pawl. The end of the lever is attached to the opposite wire, and as its oscillations advance said lever along said bar it thereby brings together 25 the wires to be spliced, or draws the wire to the post, as the case may be.

One feature of my invention consists of the 30 flexible clamp for attaching the lever to the wire or fence. This clamp is pivotally attached to the upper end of the operating-lever and substantially at right angles thereto. The clamp consists of four parts flexibly interconnected and attached to the end of said lever. The joint opposite to the attachment 35 to said lever is provided with means, herein-after described, for clasping the wire to be drawn.

Heretofore the movement of the operating-lever backwardly upon the notched bar has 40 been hampered by the difficulty of keeping at once both the actuating and retaining pawls out of engagement with the notches of said bar, and a further improvement in my present invention is the prolongation of the actuating-pawl beyond said lever adapted to enter 45 the usual slot in the retaining-pawl, and providing said extension with a shoulder, which renders it feasible to hold said pawl against said shoulder, whereby the mutual relation of 50 the actuating and retaining pawls is fixed, and by simply holding the actuating-pawl out of

engagement with the notched bar said lever can be readily moved in either direction upon said bar.

The devices aforesaid are illustrated in the 55 accompanying drawings, in which—

Figure 1 is a perspective of my invention. Fig. 2 is a detail of the aforesaid slotted hook. Fig. 3 is a detail of said flexible clamp. Fig. 4 exhibits the retaining-pawl held on the spur 60 aforesaid and in fixed relation to the actuating-pawl.

Similar letters and figures refer to similar parts throughout the several views.

A is a notched bar, to one end of which is 65 attached a chain B, provided at its extremity with a hook C. By passing the chain B around a post and hooking the hook C into said chain the bar A is held in position for working the operating-lever with its attached wire up to 70 said post.

When it is desired to draw together the adjacent ends of two wires for the purpose of splicing the same, one of said ends is slipped into the slot D, formed on hook C, obliquely 75 to the line of draft, and thereby drawn through the medium of chain B. The slot D is formed with converging walls, between which ordinary plain wire will wedge itself, and in the case of barb-wire said recess is placed behind 80 the end barb, and in either case the wire is held in line with the main body thereof.

E is a hand-lever, provided near its operating end with slot F, through which is passed the free end of the bar A, with the notches G 85 toward the handle end of said lever.

H is an actuating-pawl pivoted on the lever E in position to engage the notches G in the oscillations of said lever.

J is an arm formed on the operative end of 90 lever E, or integral therewith. To the end of arm J is pivotally attached the flexible clamp K, which consists of the parts 1 1, mutually pivoted to J at 2, and the parts 3 and 4 mutually pivoted at their outer ends and respectively pivoted at their inner ends to the parts 1 1. The outer end of the part 4 is provided with a cam-face 5, and the outer end of the part 3 is provided with a ledge 6. The wire to be drawn is placed between the cam 5 and 100 the ledge 6 and slightly compressed by moving the opposite ends of 3 and 4 inward. The

subsequent draft on said wire through lever E sufficiently tightens the pressure between said cam and ledge. The wire is released at any time by a reverse movement of the lever 5 E, and any end compression or stroke on the end of clamp K, which serves to widen the latter at the junction of parts 1 1 with 3 4, will thus remove cam 5 from ledge 6.

- L is the retaining-pawl, pivotally seated on 10 one end of arm J and provided with slot 7, in line with slot F of lever E, through which the bar A also passes. The outer end of the slot 7 is adapted to engage the notches G of bar A alternately with actuating-pawl H. 15 The engagement of the pawl L is insured by means of a spring M, coiled centrally around the pivot 8 of said pawl, with its ends abutting against lugs 9, formed on the sides of said pawl.
- 20 N is the prolongation of pawl H, provided with a shoulder 10 near its outer end. This end N of pawl H is so located relative to the pivoted end of the pawl L that when the latter is drawn toward the lever E the end N enters the slot 7, the wall of the latter rising against shoulder 10, and the operator, by throwing his finger over the pawl L, can hold the latter out of engagement with bar A, when, in moving lever E loosely on bar A, he has simply 25 30 to hold pawl H out of engagement. Arm J may be integral with lever E.

What I claim as my invention, and desire to secure by Letters Patent of the United States, is—

1. In a wire stretcher, the combination, with 35 a lever, one end of which is slotted and provided with an arm, of a flexible clamp pivotally secured to one end of the arm, and a slotted pawl pivotally secured to the other, a notch bar through the lever, and through the 40 pawl, one end of which is provided with means for securing the wire thereto, a pawl within the lever, one end of which engages with the notched bar and the other end is adapted to be engaged by the slotted portion of the other 45 pawl, whereby the two pawls may be locked out of engagement with the bar, substantially as set forth.

2. In a wire stretcher, the combination of a 50 notched bar, a lever Esleeved on said bar and provided with pawls H and L, said pawl H being provided with shoulder 10, and said pawl L with slot 7 adapted to receive the adjacent end of pawl H and abut against shoulder 10 substantially as shown and for the purpose described.

In testimony whereof I affix my signature in presence of two witnesses.

ANDREW J. UPHAM.
